UNITED STATES PATENT OFFICE.

JAMES E. MACMURRAY, OF CHICAGO, ILLINOIS.

DESIGN FOR A MAT.

SPECIFICATION forming part of Design No. 37,045, dated July 12, 1904.

Application filed May 17, 1904. Serial No. 208,474. Term of patent 14 years.

To all whom it may concern:

Be it known that I, JAMES E. MACMURRAY, a citizen of the United States, residing at Chicago, in the county of Cook and State of Illinois, have invented a new, original, and ornamental Design for a Mat, of which the following is a specification, reference being had to the accompanying drawing, which shows a perspective view of a mat embodying my new design.

What I regard as new, and desire to secure by Letters Patent, is—

The ornamental design for a mat, as herein shown.

JAMES E. MACMURRAY.
